(57) **CLAIM**

The ornamental design for a climbing tunnel, as shown and described.

DESCRIPTION

FIG. 1 is a front, right, top perspective view of a climbing tunnel showing my new design;
FIG. 2 is a front view thereof;
FIG. 3 is a back view thereof;
FIG. 4 is a left view thereof;
FIG. 5 is a right view thereof;
FIG. 6 is a top view thereof;
FIG. 7 is a bottom view thereof;
FIG. 8 is an enlarged view of the encircled area 8 of FIG. 1; and,
FIG. 9 is an enlarged view of the encircled area 9 of FIG. 4. The dash-dot broken lines show portions of the climbing tunnel and the environment that form no part of the claimed design. The dash-dot-dot broken lines depict the bounds of the enlarged views and form no part of the claimed design.

1 Claim, 9 Drawing Sheets
